SHOE SEWING MACHINE

Otto R. Haas, North Beverly, Mass., assignor to
United Shoe Machinery Corporation, Borough
of Flemington, N. J., a corporation of New
Jersey

Application May 26, 1939, Serial No. 275,942

2 Claims. (Cl. 112—57)

The present invention relates to improvements in heavily constructed shoe sewing machines of the wax thread type and is herein illustrated as being embodied in a curved hook needle lock-stitch sewing machine similar to that disclosed in prior U. S. Letters Patent of French and Meyer No. 473,870, of April 26, 1892, having a main take-up acting to set each stitch, and an auxiliary take-up to assist the main take-up in controlling the thread during the formation of each stitch.

The objects of the present invention are to improve the quality of work performed by a machine of the type referred to, to simplify the construction and to render the machine capable of operation with less noise and at a speed higher than heretofore without undesirable results.

The usual function of an auxiliary take-up in a hook needle sewing machine is to maintain a yielding tension on the thread during the formation of each stitch, and particularly while the thread is being applied to the needle hook. In the sewing machine described in the patent referred to, the auxiliary take-up is in the form of a spring actuated arm so arranged that when the stitch is being set by the main take-up, the auxiliary take-up is brought with a sudden impact against a fixed stop which is provided on the machine frame to limit the thread giving-up movement of the auxiliary take-up. Just before the auxiliary take-up is brought against the fixed stop its velocity is relatively high, and as a result of the impact and the weight of the auxiliary take-up arm, there is a tendency for the auxiliary take-up to rebound with vibratory effects, the tension on the thread together with the spring action of the auxiliary take-up causing the arm to vibrate excessively, at one or more particular frequencies. With the parts constructed as disclosed in the prior patent, the extent of vibration of the auxiliary take-up when the machine is running at relatively moderate speeds may affect successive stitches in a seam to cause them to be set in an erratic manner. Accordingly, the present invention relates to the provision in a shoe sewing machine of the wax thread type, the stitch-forming devices of which include a hook needle, a needle looper and a take-up, of a spring actuated auxiliary take-up formed of synthetic resin material arranged for movement towards and from a fixed stop on the machine frame during operation of the looper in laying the thread in the hook of the needle and against the stop with a substantial impact at the instant the stitch is being set by the main take-

up. Due to the marked ability of the synthetic resin material to absorb impacts without causing a rebound and to its lower density as compared to iron or steel from which the auxiliary take-up of the patented machine is composed, the tendency of a synthetic resin auxiliary take-up to vibrate excessively while each stitch is being set is reduced to such an extent that the stitches of a seam inserted by a machine so equipped are more accurately and uniformly set in the work than those inserted by the machine of the patent.

Other features of the invention will be more clearly understood from the following specification and the accompanying drawing in which Figure 1 is a view in left hand side elevation of the front portion of a machine embodying the present invention, and Figure 2 is a perspective view, on an enlarged scale, of the auxiliary take-up arm shown in Figure 1.

The illustrated machine is similar, except as hereinafter described, to the lockstitch outsole shoe sewing machine disclosed in the patent above referred to, the stitch-forming devices of which include a curved hook needle 2, a curved awl 4, a needle looper 6, a shuttle 8, a main take-up 10, a thread measuring arm or pull-off 12, a thread lock 14 against which each stitch is set, and an auxiliary take-up 16. The machine is intended to operate upon heavy leather materials such as the outsole indicated at 18 of a shoe, and to form each stitch in the seam, the awl 4 is actuated to penetrate the work and the needle to follow the awl through the perforations thus made until the hook of the needle projects through the work. When the needle is in this position, the looper 6 through which the needle thread is guided moves about the hook of the needle and lays the thread therein. During this movement of the looper the take-up 10 is giving up thread, and to insure that the thread is maintained under a uniform light tension, the auxiliary take-up 16 is actuated yieldingly away from a fixed stop 20 extending from the frame 45 of the machine against the resistance of a spring 22 coiled around a stud 24 on which the auxiliary take-up is fulcrumed, the other end of the spring engaging a stud 26, on the auxiliary take-up. The auxiliary take-up is in the form of an 50 arm having perforations at either end to receive the studs 24 and 26 respectively, and on the stud 26 is rotatably mounted a thread guiding pulley or sheave 28. To limit the movement of the auxiliary take-up arm under the action of the spring 22, there is threaded in the frame of the machine

a set screw 30 arranged to engage the upper side of the take-up arm. To cooperate with the fixed stop 20 against which the take-up arm is drawn by the tension on the thread as each stitch is being set, the take-up arm is provided with a projecting portion in the form of a lug 32. In addition to the yielding action of the auxiliary take-up during looping operation, the auxiliary take-up also assists in drawing past the thread lock 14 the amount of thread given up by the thread measuring arm 12 before the thread lock is closed, and before each stitch is set. To do this, the auxiliary take-up moves away from the fixed stop 20 and holds the thread yieldingly until a stitch-setting tension is applied by the main take-up to the thread. When a stitch-setting tension is applied to the thread, the auxiliary take-up is moved rapidly against the fixed stop 20 and, due to the shape and weight of the auxiliary take-up arm as well as to the yielding action of the spring 22 and the ability of the thread to stretch, there is a tendency for the auxiliary take-up arm to rebound from the stop 20 so that the tension on the thread will not be the same as when the auxiliary take-up arm remains in stationary position against the fixed stop. As a result the stitch being set may be drawn deeper into the materials of the outsole 18 when a substantial rebound occurs than when no rebound occurs. The vibratory effects caused by the rebound may not occur uniformly with each stitch, but may vary with the speed at which the machine is running, with the tension and amount of stretch in the thread being used and other factors not under the immediate control of the operator.

To reduce the vibrating effects of the auxiliary take-up in the machine of the present invention to a point where they no longer disturb the position to which the threads of stitches are drawn by the main take-up as the stitches are being set, the arm of the auxiliary take-up 16, which in the machine of the patent is composed of metal, is in the present machine replaced by an arm of substantially the same size and shape composed of synthetic resin material, suitably reenforced by textile fibres or sheets. With the use of synthetic resin materials, such as those of the phenolic or urea types, the lug 32 on the auxiliary take-up arm which engages the stop 20 absorbs to a large extent the impact produced when the lug is brought against the stop during the setting of each stitch. Due to the quality of synthetic resin material, to return to its original shape after slight deformation under impact only

5 after a relatively long interval as compared to the quick return of metallic materials to their original shapes and to the lower weight of the synthetic resin material, there is no substantial tendency for the auxiliary take-up arm to vibrate or to interfere with the setting of the stitch.

The nature and scope of the invention having been indicated, what is claimed is:

10 1. A shoe sewing machine having, in combination, a main frame, a fixed stop on the frame, stitch forming devices including a hook needle and a needle looper, a take-up, a thread measuring member, a thread lock against which each stitch is set, and a spring actuated auxiliary take-up in the form of a pivoted arm of synthetic resin material having a projecting lug at one side arranged for movement by the tension on the thread during operation of the looper to lay thread in the hook of the needle to a position spaced from the fixed stop on the frame, during operation of the take-up to set the stitch to a position with the lug against said fixed stop at the instant the stitch is being set and when the thread lock is opened to a position again spaced from said fixed stop to take up the thread drawn off from the supply by the thread measuring device, the lug being shaped when composed of said resin material to absorb a substantial proportion of the impact produced by the tension on the thread and to damp out any rebound as the stitch is being set.

20 2. A shoe sewing machine having, in combination, a main frame, a fixed stop on the frame, stitch forming devices including a hook needle and a needle looper, a take-up, a thread measuring member, a thread lock against which each stitch is set, and a spring actuated auxiliary take-up in the form of a pivoted arm arranged for movement by the tension on the thread during operation of the looper to lay thread in the hook of the needle to a position spaced from the fixed stop on the frame, during operation of the take-up to set the stitch to a position against said fixed stop at the instant the stitch is being set and when the thread lock is opened to a position again spaced from said fixed stop to take up the thread drawn off from the supply by the thread measuring device, at least one of the contacting surfaces comprised by said fixed stop and said pivoted arm being composed of synthetic resin material to absorb a substantial proportion of that impact produced by the tension on the thread and to damp out any rebound as the stitch is being set.

45 50 55 OTTO R. HAAS.
